BOOK REST.

No. 551,825.

Patented Dec. 24, 1895.

UNITED STATES PATENT OFFICE.

JOHN W. HUBBARD AND ORLANDO R. WINSLOW, OF MARSHFIELD, MISSOURI,
ASSIGNORS OF ONE-THIRD TO ANDREW J. McDOWELL, OF SAME PLACE.

BOOK-REST.

SPECIFICATION forming part of Letters Patent No. 551,825, dated December 24, 1895.

Application filed September 9, 1895. Serial No. 561,963. (No model.)

To all whom it may concern:

Be it known that we, JOHN W. HUBBARD and ORLANDO R. WINSLOW, citizens of the United States, residing at Marshfield, in the 5 county of Webster and State of Missouri, have invented a new and useful Book-Rest, of which the following is a specification.

Our invention relates to book-rests and copy-holders, our object being to provide a 10 device which carries an index-finger to mark the place for copying or reading, and operating mechanism therefor, and a clamp to hold the book open, and which holder is adjustable for different sizes of books or papers both as to 15 width and as to thickness.

With these and other objects in view our invention consists of the details of construction and the combination of parts hereinafter described, and more particularly pointed out in 20 the claims.

In the drawings, Figure 1 is a perspective view of a book-rest and copy-holder constructed in accordance with this invention. Fig. 2 is a side elevation of the same. Figs. 25 3 and 4 are detail sectional views illustrating the manner of mounting the guide-rod. Figs. 5 and 6 are detail views of the index-finger or pointer. Fig. 7 is a detail perspective view of the spring-clamp. Fig. 8 is a detail view 30 of one of the adjusting-bars.

Referring to the various parts by numerals, 1 designates a back support or plate made of wood, sheet-iron, or other suitable material, strengthened on its back by transverse cleats 35 2 and 3, which are fastened thereto by bolts 4 and thumb-nuts 5.

6 designates a stiff wire brace suitably hinged at 7 to swing into folded position or be retracted to supporting position. This 40 supporting-plate 1 is provided with legs 8, and adjacent thereto in horizontal alignment along the front face of plate 1 are rests 9 of cast metal, preferably in the form of brackets. These support the foot of the book. The top 45 thereof is held in place by a spring-clamp 10, centrally provided with a finger-loop or button 12 and formed at either end with an arched portion 13, outwardly and downwardly bent portion 14, a coiled portion 15, which receives 50 the pivot-screw 16, and a straight tension

member 17 provided with a handle-loop 18, and resting against the retaining screw or lug 19.

Parallel with the left side of supporting-plate 1 is guide-rod 23, which is held in adjustable alignment by means of two similar 55 arms, the upper arm 21 and the lower arm 22, which are pivoted against the edge of plate 1 by means of set-screws 23, so as to swing in the plane of said vertical edge. On their outer ends these arms carry bearing-spindles 24, 60 bolted thereto at right angles, so as to turn in sockets 25 provided in said arms. These bearing-spindles 24 comprise the journal end 26, threaded to receive nut 27, the transversely-perforated block 28, provided with thumb-screw 29 and adapted to receive the guide-rod 20, and the stub-axle 30 on the outer end, on 65 which the belt-pulleys 31 are journaled. Stub-axes 30 are threaded at their outer ends 32 to receive nuts 33, which secure pulleys 31 thereon. The outer flange of the lower pulley is enlarged and milled to provide an adjusting-wheel 34. These pulleys are grooved to receive a round leather endless belt 35, which is secured at its meeting ends 36 to the middle 70 portion of projecting end 37 of index-finger or pointer 38. This index-finger is provided with a transverse sleeve 39, threaded over guide-rod 20, and is continued on in an arm 40, which extends substantially across plate 1, and is 75 provided with a telescoping extension 41, for use with the back extension, presently to be explained.

In case plate 1 is not wide enough to hold the ledger, bank-book, or paper that is to be 80 copied or read, we provide an extension-plate 42, provided with cleats, legs, and bracket-rests similar to plate 1. Secured to the cleats thereof are adjusting-bars 43, perforated with a plurality of holes 44, which are adapted to 85 seat on bolts 4 and be secured in adjustment by thumb-nuts 5. The upper bar 43 is backwardly curved at 45 to receive the back of the open book. The lower bar is below the horizontal bracket-rests 9, and therefore out 90 of line with the book and not curved.

In the use of our book-rest and copy-holder, if a small book or a single sheet is to be held, the back brace 6 is adjusted to support back plate 1 at suitable inclination, and the sheet 100

is placed on rests 9 with its upper end securely held by spring-clamp 10. The arms 21 and 22 are swung up enough to carry guide-rod 20 into a plane just above the surface of 5 supporting-plate 1 and are there secured by set-screws 23. The index-finger 38 is now ad-justed to the proper position on the page by turning adjusting-wheel 34, and thereby re-volving endless belt 35, which carries said 10 finger. If the belt slips on pulleys 31, it may be stretched by tightening the meeting ends 36. When the page is copied and it is de-sired to turn it, index-finger 38 is swung up 15 out of the way. The torsion of belt 35 tends to restore said finger and to keep it in place.

If the book is too wide for plate 1, the ex-tension-plate 42 is suitably adjusted by means 20 of holes 44 and nuts 5. The book is rested against curve 45 and opened, and index-fin-25 ger extension 41 is pulled out, so as to indicate on the right-hand page.

Changes in the form, proportion and the minor details of construction may be resorted to without departing from the principle or 25 sacrificing any of the advantages of this in-vention.

What we claim is—

1. In a book rest, the combination with a suitable supporting plate braced at its rear 30 and provided at its foot with bracket rests and at its head with a spring clamp, of upper and lower arms pivoted to swing in a plane perpen-dicular to said plate and connected at their outer ends by a guide bar swiveled in said 35 ends, an index finger adapted to reciprocate along said guide bar, and mechanism to recip-rocate said index finger, substantially as de-scribed.

2. In a book rest, the combination with a suitable supporting plate braced at its rear 40 and provided at its foot with bracket rests and at its head with a spring clamp, of upper and

lower arms pivoted to swing in a plane perpen-dicular to said plate, each of said arms being provided in its outer end with a laterally pro-45 jecting bearing spindle comprising a shaft journaled in said arm, a transversely perfo-rated box for a guide bar and a stub axle pro-vided with a belt pulley, a guide bar adjusted in said perforated boxes by means of set screws 50 provided therein, an endless belt passing over said pulleys, an index finger provided with a sleeve arranged to reciprocate on said guide rod, and attached at its adjacent end to said belt and having its farther end adapted to ex-tend transversely across said plate, and a 55 hand wheel secured to said lower pulley whereby said index finger may be adjusted along the face of said plate, substantially as 60 described.

3. In a book rest, the combination with a suitable supporting plate, braced at its rear and provided with bracket rests at its foot, and with a spring clamp at its head, and with a re-ciprocating index finger at one side, said finger 65 being telescopically extensible, of an exten-sion plate braced at its rear and similarly pro-vided with bracket rests, and also provided with laterally extending parallel bars secured to the rear of said extension plate and having 70 a plurality of perforations through their outer ends, by means of which said bars may be se-cured to and longitudinally adjusted on the rear of said supporting plate by means of thumb screws provided on said latter plate, 75 substantially as described.

In testimony that we claim the foregoing as our own we have hereto affixed our signatures in the presence of two witnesses.

JOHN W. HUBBARD.

ORLANDO R. WINSLOW.
